[57] CLAIM

The ornamental design for a furniture spring hook, as
shown and described.

DESCRIPTION

FIG. 1 is a top perspective view of a furniture spring
hook showing my new design;

FIG. 2 is a side elevational view thereof;

FIG. 3 is an opposite side elevational view thereof;

FIG. 4 is a bottom plan view thereof;

FIG. 5 is a top plan view thereof;

FIG. 6 is an end elevational view thereof;

FIG. 7 is an opposite end elevational view thereof; and,

FIG. 8 is a top perspective view of a second embodiment
of the invention.

The appearances of the undisclosed top, bottom, and end
views of the second embodiment are identical to said
views of the first embodiment.

FIG.1.

FIG.2.

FIG.3.

FIG.4.

FIG.5.

FIG.6.

FIG.7.

FIG.8.
